Attorney

UNITED STATES PATENT OFFICE.

CARL SASS, OF HAMBURG-HARVESTEHUEDE, GERMANY.

CLEANSING BOX FOR USE IN SEWERAGE PIPES.

Application filed August 28, 1926, Serial No. 132,253, and in Germany May 7, 1925.

The invention provides the hereinafter described improved cleansing box for use in a sewerage pipe and has for its object to provide a cleansing box having an improved 5 intercepting device capable of regulating and cutting off an inner space.

Sewerage pipes having interior intercepting devices are already known wherein a pressed metal plate provided with stamped 10 slits rests on a bend applied to the tube walling to swing therein.

These known devices have the disadvantage that when the sewerage matter is cleaned out and the metal plate is dis- 15 mantled the interception of matter within the tube is suspended and animals are enabled to pass.

This disadvantage is obviated by the present invention which consists in providing 20 the cleansing box with an interception shutter capable of cutting off an inner space said shutter consisting of several sector shaped metal rods arranged parallel one to the other and constructed to permit of single dis- 25 mantling.

By this special arrangement it is made possible for the independent parallel sector shaped rods, when the sewerage matter is cleansed to be independently taken to pieces 30 and to be pivotally raised only so far as the sewerage matter to be cleansed necessitates.

Still further the device possesses the advantage that the single rods can be easily cleansed and can be interchangeable.

The invention is illustrated by way of example in the accompanying drawing upon which similar letters of reference denote corresponding parts.

Fig. 1 shows the cleansing box in longitudinal section, and

Fig. 2 is a section taken along the line A—B of Fig. 1.

The cleansing box *a* has two longitudi-

nally connected tubes *b*, *c*, of which the tube *b* is shut off by a rearwardly actuated piv- 45 oted valve *d* which can be taken to pieces in the box having two trunnions *e* bearing in grooves *f* situated on the inner walls of the box.

Within the cleansing box *a* is an intercep- 50 tion shutter composed of several independent sector formed metal rods *g* parallel to one another. The independent metal rods *g* have at their upper ends a perforation *h* by means of which they are pivoted on a 55 bearing bolt *i* and are separated by distance sleeves *k* lying adjacent the various rods. The bearing bolt *i* has its ends bearing in a box casing *l* which latter is conveniently attached to a partition wall *m* of the box. 60

The independent sector formed rods *g* normally abut against the edge *n* of a flange of the box casing *l*.

Having now described my invention what I claim and desire to secure by Letters 65 Patent is:—

1. A sewer grate comprising a supporting bolt, a plurality of juxtaposed, parallel sector-shaped rods having toothed lower ends, a means for suspending the upper ends of 70 said rods rotatably independently and exchangeably from said common support.

2. A sewer grate construction comprising in combination with a partition wall of the sewer, and a box attached thereto, a grate 75 composed of a plurality of juxtaposed sector-shaped parallel rods, perforated near their upper ends having toothed lower ends, a common bearing bolt resting with its ends in the walls of said box, and sleeves on said bolt separating said rods from each other, said rods allowing the free passage of the excrements or faeces, and preventing the passage of animals. 80

In testimony whereof I affix my signature.
CARL SASS.
